UNITED STATES PATENT OFFICE.

CHARLES A. MCNEAL, OF COLUMBUS, OHIO.

ILLUMINATED SIGN.

1,267,571.

Specification of Letters Patent.

Patented May 28, 1918.

Application filed May 14, 1917. Serial No. 168,435.

To all whom it may concern:

Be it known that I, CHARLES A. MCNEAL, a citizen of the United States, resident of Columbus, in the county of Franklin and State of Ohio, have made a certain new and useful Invention in Illuminated Signs; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a front view of the sign.

Fig. 2 is a section on the line 2—2, Fig. 1.

Fig. 3 is a section on the line 3—3, Fig. 1.

The invention has relation to illuminated signs, having for its object to light the 20 background of a sign and the letters or design, from the rays of the same lamp or lamps, in contrasting colors. Other objects and advantages will hereinafter appear.

The invention consists in the novel construction and combinations of parts, as hereinafter set forth.

In the accompanying drawings illustrating the invention, which is designed primarily for an exteriorly lighted sign, the 30 numeral 2 designates a portion of a sign, including the letters S and T, formed usually by disk reflectors 3, struck outwardly from the sheet metal of said face plate and connected to the face plate each by a narrow 35 neck or necks 4, said reflectors set at different angles to said plate, for the purpose hereinafter explained.

The illumination is accomplished by lamps or incandescent bulbs 5, 5, located 40 within or at one side of the letters or design, and projecting forwardly of the reflectors 3.

The face plate is colored red, blue, green, or other color contrasting to white, as may 45 be desired, the tips 6 of the bulbs being colored to harmonize or correspond with the color of the background or face plate, the sides of said bulbs being left uncolored as usual, the rays of light transmitted to the observer or forwardly from said tips being of the same color as that of the background or face plate, so that the bulbs themselves are not seen, being lost or coalescing in the background.

50 55 The disk reflectors are arranged in groups

around the respective lamps or light bulbs, and are set at such angles that the radiating rays of light from the lamps shall be reflected straightforward to the observer. The angles at which the reflectors are set to the 60 face plate will be the same in those reflectors that are equally distant from the lamp, but in those that are more distant, the angular relation to the face plate will be greater than in those nearer. In all of the 65 reflectors the inclination will be toward the lamp.

The background being of the same color and tone as the lamp tip, the result is a vividly colored background, wherein the 70 lamps are lost or are not seen, and an intense white letter or sign, both lighted from the same lamp or lamps, there being at the same time a great saving in operative expense, as no lamps at all are set in the letters and fewer lamps are required to illuminate the sign.

The letters are usually white, and the reflectors may be polished metal or faced with porcelain, mercury, or other suitable reflecting material. The tips of the bulbs may be dipped in coloring medium, or colored light transmitting hoods may be used. The background and the lamp tips can be made white and the reflectors and letters colored if 85 desired.

The following combinations are enabled to be obtained:

1st. A colored transparent lamp tip corresponding in color to that of the background of the sign, and reflectors illuminated by the white light from the uncolored side of the lamp and in rear of the colored lamp tip, reflecting the light rays straightforward to the observer, the result being 95 that the letters or design stand out in white light upon a colored background.

2nd. A colored transparent lamp tip of a contrasting color to that of the background, the result being that the lamp stands 100 out as a contrasting spot of color on the background, the letters or design showing in white.

3rd. A colored transparent lamp tip of a color corresponding to that of the background, with the reflectors of a color contrasting to that of the background. The coloring of the reflectors is accomplished by using mirrored colored glass, or by a thin film of transparent color or paint, over 110

a metallic reflector, the effect being to illuminate the letters or design in vari-colored light from the one source of white light.

4th. A colored transparent lamp tip of a color contrasting to that of the background, with vari-colored reflectors.

Other color combinations are possible, but these are sufficient to explain the object of the invention. In the combinations outlined 10 white and black are considered as colors.

The lamps are preferably set in the open spaces in the letters having open spaces, but may be set in other suitable places adjacent to the letters of the sign.

15. I claim:

In an illuminated sign, a face plate having a reflecting surface, a source of light forward of said face plate, a bulb or globe surrounding the same and having tip and side portions, reflectors set in the outline of 20 a letter or design and unequally distant

from, in the rear of and grouped around said source of light, said reflectors having different inclinations with respect to said face plate, toward and facing the source of light, the inclinations varying according to the distance of the reflector from said light and being decreased in those reflectors that are nearer the light, to reflect the rays incident to corresponding portions of all of 25 the reflectors outwardly in parallel lines, the reflectors outwardly in parallel lines, direct rays from said source being transmitted through the tip portion of the bulb to the observer, the tip and side portions of the bulb being colored differently and the reflecting surface of said face plate being colored to harmonize with the color of said tip portion and transmitting rays of light from said source to the observer.

30 In testimony whereof I affix my signature. 35

CHAS. A. McNEAL.
